UNITED STATES PATENT OFFICE

94,940

DESIGN FOR A SHOE

Albert F. Bancroft, Newton, Mass., assignor to
Bancroft Walker Co., Waltham, Mass., a cor-
poration of Massachusetts

Application December 7, 1934, Serial No. 54,333

Term of patent 3½ years

To all whom it may concern:

Be it known that I, Albert F. Bancroft, a citizen of the United States, residing at Newton, in the county of Middlesex and Commonwealth of Massachusetts, have invented a new, original, and ornamental Design for a Shoe, of which the following is a specification, reference being had to the accompanying drawing, forming a part thereof, in which

Fig. 1 is a view in side elevation of a shoe showing my design; and

Fig. 2 is a plan view of the shoe.

The ornamental effect of my novel design resides in a wide loop-shaped band extending from

the sole line at one side of the shank across the vamp to a corresponding point on the other side of the shank and flaring in width at both ends, in combination with a folded ribbon-like element located at the throat of the vamp and having notched divergent ends which overlap the band above mentioned at spaced points in the bend of its loop.

I claim:

The ornamental design for a shoe substantially as shown and described.

In testimony whereof, I have affixed my signature hereto.

ALBERT F. BANCROFT.
